UNITED STATES PATENT OFFICE.

THOMAS W. BROWN, OF CHICAGO, ILLINOIS.

MOUTH-PROTECTOR.

1,302,004.

Specification of Letters Patent. Patented Apr. 29, 1919.

Application filed January 16, 1919. Serial No. 271,458.

To all whom it may concern:

Be it known that I, THOMAS W. BROWN, a citizen of the United States, and a resident of Chicago, Cook county, and State of Illinois, have invented certain new and useful Improvements in Mouth-Protectors, of which the following is declared to be a full, clear, and exact description.

This invention relates to mouth protectors, and its principal object is to provide cushioning means for protecting the teeth, lips and other parts of the mouths of boxers, pugilists and the like, from blows upon the jaws or adjacent parts of the face. As is well known, there is a tendency for boxers especially amateurs, while boxing or sparring, to slightly open their mouths or at least they frequently neglect to tightly close down their teeth, the result being that a blow upon the lower jaw will have the effect of forcibly bringing them together, sometimes breaking off some of the teeth, and also producing jars that are transmitted to the head above the mouth. Again, hard punches on the lips cause lacerations on the inside of the lips by reason of the sharp forcible contact with the teeth. With the present device in place, all of said injurious results from blows upon the mouth or jaws are practically eliminated. The invention consists in a resilient pad or cushioning member, adapted to be gripped between the teeth of the user and having webs extending up and down along the outer edge portion and adapted to be interposed between the teeth and lips of the user, thus protecting (when held in place), the teeth, lips and other parts of the mouth of the user against hard blows on the face at places adjacent the mouth. The invention further consists in the other novel features hereinafter fully set forth and claimed.

The invention is clearly illustrated in the accompanying drawing, in which:

Figure 1 is a side elevation of a mouth protector embodying a simple form of the present invention, shown in place in the mouth of a user; Fig. 2 is a central, vertical, longitudinal section through the device, and Fig. 3 is a perspective view of the device.

Referring to said drawing, the reference character 4, designates a substantially U-shaped resilient body, the upper and lower

faces of which may be flat, and, if desired, formed with depressions 5, to receive the cusps of the teeth of the user. At the front or bend of the body 4, is a web 6, which projects up and down, as at 7, 8, from the front edge portion. The upper and lower edges of the web 6, merge into the top and bottom of the body portion as shown. The edge portions of the web 6, are preferably thinned down, and the marginal edges are made smooth to avoid irritation.

It may be found desirable to provide an insert 9, in the body portion to reinforce the same and prevent the user from biting through the device. Such insert is made of tough material, such as leather, fiber or the like and is embedded in the device before vulcanization. The material, of which the device is made, may comprise rubber or other resilient compositions capable of being molded into proper form.

In practice the protectors may be formed of several sizes and shapes to fit the average mouths, but for the more perfect and expensive protectors it is preferable to take a cast of the user's teeth and from it produce a protector that more nearly conforms to the shape of the mouth and teeth. In this case the indentations will match up with the teeth and greater comfort is thereby obtained. In any case the U-shaped body should be wide enough to project beyond the sides of the teeth and contact with the insides of the lips and cheeks of the user.

In use the protector is inserted between the teeth, and the teeth closed down upon the body portion; with the web extending between the lips and teeth. It is obvious that upward blows upon the lower jaw will be transmitted to the upper jaw, but nevertheless, through the protecting, resilient pad or body, 4, which cushions the blow and prevents the teeth from being broken. Likewise blows on the cheeks will be cushioned by the projecting edge portions of the pad, and much of the force of blows on the front of the mouth will be absorbed and cushioned by the web 6, consequently, the danger of cutting or lacerating the lips will be reduced to a minimum.

More or less variations of the exact details of construction is possible without departing from the spirit of this invention; I desire,

therefore, not to limit myself to the exact form of the construction shown and described, but intend, in the following claims, to point out all of the invention disclosed herein.

I claim as new and desire to secure by Letters Patent:

1. A mouth protector of the character described, comprising a substantially U-shaped, 10 resilient body portion, forming the entire U-bend and adapted to be gripped between the teeth of the user, and having a web portion along its forward edge; substantially as and for the purpose set forth.
- 15 2. A mouth protector of the character described, comprising a substantially U-shaped resilient body portion, forming the entire U-bend and adapted to be gripped between the teeth of the user and having an integrally formed web extending up and down

from its forward edge; substantially as and for the purpose set forth.

3. A mouth protector of the character described, comprising a resilient pad, adapted to be gripped between the teeth of the user 25 and formed with a web at its forward edge, arranged to extend between the lips and teeth of the user, and a strip of stout material embedded in said pad; substantially as and for the purpose set forth.

4. A mouth protector of the character described, comprising a substantially U-shaped resilient body portion formed with tooth indentations in its upper and lower faces and adapted to be gripped between the teeth 35 of the user, and having a web portion along its forward edge; substantially as and for the purpose set forth.

THOMAS W. BROWN.
